UNITED STATES PATENT OFFICE.

ISAAC E. PALMER, OF MIDDLETOWN, CONNECTICUT.

BEDSTEAD CANOPY-FRAME.

SPECIFICATION forming part of Letters Patent No. 665,126, dated January 1, 1901.

Application filed October 24, 1899. Serial No. 734,616. (No model.)

To all whom it may concern:

Be it known that I, ISAAC E. PALMER, a citizen of the United States, and a resident of Middletown, in the county of Middlesex and 5 State of Connecticut, have invented a new and useful Improvement in Bedstead Canopy-Frames, of which the following is a specification.

My invention relates to an improvement in 10 bedstead canopy-supports, the objects being to provide a structure in which the canopy may be readily moved into position to envelop the bed and out of position when so desired, and to provide a support which may be remov- 15 ably supported by the bed, which will be very strong, and which will be thoroughly adjustable for different widths of beds and also ad- justable as to height.

A still further object is to provide a canopy- 20 support which may be folded into a very compact bundle for shipping purposes or for putting away when not in use in connection with a bed.

A practical embodiment of my invention is 25 represented in the accompanying drawings, in which—

Figure 1 represents a view of a bedstead in 30 side elevation, the canopy-support carried thereby, and a canopy carried by the support, the said canopy being in position to envelop 35 the bed. Fig. 2 is a top plan view of the same. Fig. 3 is a vertical central section through a portion of a bedstead and the parts supported thereby, the canopy being repre- 40 sented in its position at the head of the bed- stead, as when not in use. Fig. 4 is a trans- 45 verse vertical section taken in the plane of the line 4 4 of Fig. 3. Fig. 5 is a detail view of the upper portions of the pair of support- 50 ing-legs of the support and the reach, show- ing the legs spread to the limit of their out- ward movement. Fig. 5^a is a similar view showing the legs at the limit of their inward movement. Fig. 6 is a vertical transverse 55 section through a bedstead, showing a modi- fied form of canopy-support. Fig. 7 is an 60 enlarged detail view showing the device for se- curing each of the supporting-legs to the head-board of the bedstead. Fig. 8 is a side 65 view of the canopy-support in its folded po- sition, and Fig. 9 is an edge view of the same.

The canopy-support comprises a pair of sup-

porting-legs A A', hinged together at their upper ends, and a longitudinally-adjustable top reach B, which is engaged with the pair 55 of supporting-legs at their upper ends.

In my preferred form the canopy-support is made vertically adjustable by making the legs A A' extensible and contractible. In the accompanying drawings I have repre- 60 sented these legs as being composed of lower sections a a' and upper sections a² a³, the upper and lower sections of the legs overlapping each other and having a pin-and-slot connection, together with a clamping device 65 a⁴ for securing the legs in any desired adjustment, thus accommodating the support to rooms of different heights and canopies of different depths. The supporting-legs A A' are provided with feet C C', respectively, 70 which feet are preferably hinged to the lower ends of the said legs, so that they may be folded up against the legs when not in use. The supporting-legs A A' may be adjusted to any desired distance apart and held in 75 such adjustment, in the present instance by means of a pair of flexible cords which extend across the space between the feet C C', the said cords being permanently secured to one of the said feet, if so desired, and being 80 removably secured to the other foot in some suitable manner.

The top reach B is fitted to be adjusted longitudinally, so that it may be extended over the bed or slid back to one end thereof 85 in the following manner: A pair of short arms D D' are hinged to the legs A A' near the upper ends of the legs, the inner ends of the said arms D D' being hinged to the socket D², arranged directly beneath the hinged upper 90 ends of the legs. In the present instance the outer ends of the arms D D' are hinged to clips d d', securely fastened to the supporting-legs A A'. The upper ends of the legs A A' are hinged together by a loose coup- 95 ling D³, so as to leave a sufficient space be- tween the ends of the legs to permit the reach B to be slid between them. This reach B also has a sliding engagement with the socket D², carried by the arms D D'. This arrange- 100 ment gives the reach an extended bearing and also permits the legs to be adjusted out- wardly and inwardly without interfering with the sliding engagement of the reach therewith.

The free end of the reach B is provided with a suitable socket b for the reception therein of the top of the canopy E, which canopy may be of any desired form or construction to suit different requirements.

The under edge of the reach B is provided with a number of notches b', which serve to engage the coupling D³ when the reach is extended, so as to insure the holding of the same in position. The several notches render the reach adjustable for use in connection with different sizes of canopies and to suit the requirements of different people as to the location of the hoop of the canopy nearer to or farther away from the head of the bed.

For convenience in packing or folding the several parts of the support the reach is preferably formed in two sections hinged together at b², the hinge being constructed so as not to interfere with the sliding of the reach through the socket D² and the coupling D³.

The operation of my device is as follows: When it is desired to use the support in connection with a bed, the two legs A A' are placed in an upright position along one end of the bedstead—as, for instance, the head-board. The legs are then spread apart until the feet C C' are located in close proximity to the side rails of the bedstead. The flexible connections c c' are then manipulated to prevent the further spreading of the legs and the feet. The supporting-legs are then extended or contracted to adjust the height of the canopy with respect to the bedstead. The canopy may then be engaged with the free end of the reach B and the reach adjusted longitudinally to the desired position. When it is wished to remove the canopy from use, but not remove it from the support, the reach B is slid rearwardly until the hoop of the canopy assumes a slanting position at one end of the bed, the curtains of the canopy being drawn over the said end of the bed.

In the modified form shown in Figs. 6 and 7 the supporting-legs are adjustably secured to the end board of the bedstead by means of suitable clamps F, which embrace the said legs. In this form the legs may be made of continuous strips, the desired height being readily obtained by manipulating the clamping devices F. In this form the use of the feet C C' is obviated.

By the use of a pair of legs I obtain a very rigid structure capable of sustaining a canopy of any size without danger of bending the support, the support at the same time being made very light.

It is evident that slight changes might be resorted to in the form and arrangement of the several parts without departing from the spirit and scope of my invention. Hence I do not wish to limit myself strictly to the structure herein set forth; but

What I claim is—

1. A bedstead canopy-frame comprising a pair of supporting-legs connected at their upper ends, a curved top reach supported thereby and means for adjustably securing the curved portion of the top reach to the legs in different positions in the direction of its length, substantially as set forth. 65

2. A bedstead canopy-frame comprising a pair of supporting-legs and an adjustable top reach carried thereby, the said top reach being made in sections hinged together, substantially as set forth. 75

3. A bedstead canopy-frame comprising a pair of supporting-legs hinged together at their upper ends, a curved top reach supported at the hinge connection of the legs and means for adjustably securing the curved portion of the reach to the legs whereby the reach is supported at different angles with respect thereto, substantially as set forth. 80

4. A bedstead canopy-frame comprising a top reach, a pair of supporting-legs connected to open and close, means for connecting the reach with the legs and feet hinged to the lower ends of the legs, substantially as set forth. 85

5. A bedstead canopy-frame comprising a pair of supporting-legs, a loose coupling for hinging the legs together at their upper ends and a curved top reach fitted to slide through the loose coupling whereby the angle of the reach is changed with respect to the supporting-legs, substantially as set forth. 95

6. A bedstead canopy-frame comprising a curved top reach, a pair of supporting-legs therefor, a loose coupling for hinging the legs together at their upper ends, through which the top reach is fitted to slide, to change the angle of the reach with respect to the legs, and a socket supported by the legs in position to also receive the reach therein for supporting the reach in its different adjustments, substantially as set forth. 100

In testimony that I claim the foregoing as my invention I have signed my name, in presence of two witnesses, this 18th day of October, 1899. 110

ISAAC E. PALMER.
